UNITED STATES PATENT OFFICE.

JOHN P. RASMUSSEN, OF IRONWOOD, MICHIGAN, ASSIGNOR OF ONE-HALF TO GEORGE A. CURRY, OF IRONWOOD, MICHIGAN.

DEVICE FOR HOLDING CARPETS.

1,383,565.

Specification of Letters Patent.

Patented July 5, 1921.

Application filed January 21, 1921. Serial No. 438,984.

To all whom it may concern:

Be it known that I, JOHN P. RASMUSSEN, a citizen of the United States, residing at Ironwood, in the county of Gogebic and

5 State of Michigan, have invented certain new and useful Improvements in Devices for Holding Carpets, of which the following is a specification.

This invention relates to devices for holding 10 carpets or other floor coverings upon stairways, and it comprises a pair of angular brackets adapted to be arranged beneath the carpet at the corner of the steps, each of said brackets being provided with an outwardly extending member adapted to form a support, a rod arranged between said supports and slightly spaced from the steps, and securing members extending through 15 said supports and engaging said rod.

20 In the present invention, I have provided a device for holding carpets on steps, in which tacks or other fastening means do not pierce the carpet, and thus mar it. At the back of each step, an angular bracket is arranged at each side of the carpet, the body portion of the back being covered by the carpet after the carpet is laid. A supporting member is carried by each of these brackets, the supporting member being arranged parallel to the edge of the carpet and adapted to be arranged adjacent said edge. After the carpet has been laid, a rod is disposed between the two brackets to hold the carpet in place, and securing members 35 are passed through the supports to secure the rod thereto.

In the accompanying drawings, I have shown one embodiment of the invention. In this showing:

40 Figure 1 is a detail perspective view of a portion of a stairway showing the invention applied,

Fig. 2 is a sectional view of the carpet holder,

45 Fig. 3 is a detail view of the securing elements,

Fig. 4 is a perspective view of the pair of brackets, and,

50 Fig. 5 is a plan view of the blank used in forming the bracket.

Referring to the drawings, the reference numeral 1 designates the tread of a step, and 2 the riser of the step forming a portion of a stairway. A strip of carpet 3, or other 55 covering, is arranged on the stairway in the

usual manner, and my improved carpet securing means is employed, being arranged at the intersection of the top and back of the step.

The carpet holder comprises a pair of 60 brackets which are similar in construction, and a description of one will suffice. Each of the brackets comprises a horizontal arm 4, adapted to be arranged on the tread of the step, and a vertical arm 5 adapted to 65 be arranged adjacent the riser of the step. These members are provided with openings 6, for the reception of screws, nails, or other suitable fastening elements. The brackets are best arranged adjacent the side edge of 70 the carpet. On the outer end of each of the brackets, there is provided a supporting member 7, arranged at an angle to the body portion of the bracket and substantially parallel to the edge 8 of the carpet. 75

Referring to Fig. 5 of the drawings, the brackets are formed of a single piece of material which is bent on the dotted line 9, to form the arms 4 and 5 of the bracket, and then bent on the dotted line 10, to arrange 80 the ears 11 and 12 adjacent each other. The outer edge 13 of the ears is rounded to slightly space them from each other (see Fig. 2) and one of the members is provided with a lip 14, adapted to be bent over the 85 edge of the other member to secure them to each other. The inner portion 11 of the supporting member is provided with an opening 15, and a similar opening 16 is arranged in the outer portion of the supporting member, 90 the openings being adapted to register with each other. The opening 16 is provided with a slot 17, for the passage of a pin 18 carried by a rod securing member 19. It will be apparent that the member 19 may be passed 95 through the openings 15 and 16, and when the pin 18 is arranged in alinement with the slot 17, the securing member 19 may be passed inwardly until the head 20 engages the outer edge of the supporting member 12. 100 By turning the securing member until the slot 17 and pin 18 are out of alinement, accidental displacing of the securing member is avoided.

Referring to Fig. 2 of the drawings, the 105 securing members are adapted to enter the ends of a hollow rod 21, the length of which is substantially equal to the distance between the brackets, the rod 21 being thus held in position by the securing members 110

slightly spaced from the top and back of the step to hold the carpet in position.

When a carpet is to be laid, the brackets are first placed in position at the proper distance from each other. The carpet is then arranged on the stairway, and the rods 21 properly positioned with their ends in alinement with the openings 15 and 16. The securing members 19 are inserted and turned 10 a portion of a revolution to lock them in position. When the carpet is to be taken up, the securing members are first removed and the rods 21 thus released, may be removed to loosen the carpet. If another carpet is to be laid, the brackets may be left on the stairway, or they may be removed by removing the fastening elements from the opening 6.

When the carpet is laid, the body portion 20 of the brackets are covered, and the only parts of the fastening elements which are visible are the rods 21, the supporting members 12, and the heads 20 of the securing elements. These parts may be made ornamental in appearance, and thus produce a more pleasing effect.

It is to be understood that the form of my invention herewith shown and described is to be taken as a preferred example of the 30 same, and that various changes in the shape, size, and arrangement of parts may be resorted to without departing from the spirit of the invention or the scope of the subjoined claims.

Having thus described my invention, I claim:

1. A stairway carpet holding device, com-

prising a pair of L-shaped brackets adapted to fit in the corner between the tread and riser of the step, one of said brackets being 40 arranged adjacent each edge of the carpet, a plate secured to each arm of said bracket, said plates being arranged adjacent each other and substantially parallel to the edge of the carpet, and being provided with registering openings, a rod of substantially the same length as the distance between said brackets, and securing means passing through the openings in said plates and secured in the ends of said rod. 50

2. A stairway carpet holding device, comprising a pair of L-shaped brackets adapted to fit in the corner between the tread and riser of the step, one of said brackets being arranged adjacent each edge of the carpet, 55 a plate secured to each arm of said bracket, said plates being arranged adjacent each other and substantially parallel to the edge of the carpet and being provided with registering openings, the opening in the outer 60 plate being provided with a groove, securing means arranged in the openings in said plates and extending inwardly, said securing means being provided with pins adapted to enter said grooves to retain the securing 65 means in position, and a hollow rod disposed between said brackets, the ends of the securing means being received in said rod.

In testimony whereof I affix my signature in presence of two witnesses.

JOHN P. RASMUSSEN
